UNITED STATES PATENT OFFICE.

CHAUNCEY H. GUARD, OF BROWNSVILLE, NEW YORK, ASSIGNOR TO J. A. SCROGGS AND C. H. GUARD.

MACHINE FOR BORING AND MORTISING HUBS.

Specification of Letters Patent No. 18,307, dated July 24, 1855.

To all whom it may concern:

Be it known that I, CHAUNCEY H. GUARD, of Brownsville, in the county of Jefferson and State of New York, have invented sun-
5 dry new and useful Improvements in Ma-
chinery Used in the Manufacture of Car-
riage-Wheels; and I do hereby declare that
the following is a full and exact description
thereof, reference being had to the accompa-
10 nying drawings, making a part of this speci-
fication.

Figure 1, is a top view of my improved
machine; Fig. 2, a longitudinal vertical sec-
15 tion, in the line y, y , of Fig. 1; Fig. 3, a
transverse section in the line w, w , of Fig. 1;
Fig. 4, a transverse section in the line z, z ,
of Fig. 1; and Figs. 5, and 6, represent por-
tions of the machine.

Similar letters indicate like parts in all
20 the figures.

The frame of the said machine may be
constructed in any well known or usual man-
ner.

A carriage composed of two independent
25 parts B, and C, which are connected to each
other by the screw rod u , is placed between
the sides D, D, of the machine, and is sus-
tained in such a manner that the said car-
riage, or either section of it, may be moved
30 lengthwise between the said sides of the
frame. A crank handled set screw v , passes
through one end of the frame of the machine
and enters a female screw secured in the
largest section B, of the aforesaid carriage;
35 and a similar set screw w , passes through
the opposite end of the frame and enters a
female screw secured in the section C, of the
carriage. By unscrewing one of the said set
screws and screwing up the other, the car-
40 riage can be moved in either direction at
pleasure. And the respective sections B, C,
of the carriage, can be made to approach or
recede from each other, by screwing up, or
unscrewing, the nut on the screw rod u , and
45 operating either one or the other of the set
screws w , or v .

The chucks a', a' , which receive and hold
a hub A, while it is being mortised, and
while the spokes are being driven into it, are
50 combined with the inner ends of the sections
B, C, of the said carriage, by means of suit-
able boxes which receive the journals of said
chucks. The said boxes are secured to the
sections of the carriage and to the caps B',
55 C'; and the said caps are secured in their

proper positions upon the sections of the car-
riage, by set screws, substantially as repre-
sented in Figs. 1, 2, and 5. It will there-
fore be perceived that the chucks a', a' , can
be placed nearer to, or removed farther from
each other, to adapt them to the reception of
hubs of different lengths. After a hub has
been fitted into the said chucks, the nut on
the screw rod u , is screwed up to hold the
hub securely in its position; and then by
60 turning the set screws w , and v , in opposite
directions, the hub may be moved longitudi-
nally in either direction to enable the augers
or bits to bore the requisite preliminary
holes, and the chisels to form mortises of any
65 desired length in the said hub.

The bits i, i , which bore the requisite
holes in the hub, are placed in the rotat-
ing holders m, m , which work in the bear-
ings r, r , which are secured to the outer sides
70 D, D, of the frame, in such positions that the
bits will be held in the same horizontal line
with each other, and point toward the axis
of the hub.

From the crown of each of the bearings
 r, r , a standard s , rises, which standards sup-
port the driving shaft j . Motion is commu-
nicated from the said driving shaft to the
bit holders m, m , by means of the cog wheels
 k, k , on the ends of the said shaft, which
work into the elongated pinions l, l , on the
outer ends of said bit holders. The points
of the bits i, i , are made to slowly approach
each other, or to rapidly recede from each
other as they are rotated, by means of right
80 and left hand screw threads g', g' , and h', h' ,
of different proportions, on their periph-
eries, and movable segments o, o , and n, n ,
of female screws, which fit the said screw
threads, and which are arranged in such a
85 manner that either pair of them can be
thrown into or out of gear with the said
screw threads at pleasure; viz, hanging sup-
ports q, q , descend from the under side of
the bearings m, m , whose open mouths re-
ceive the levers p, p , and in which they are
90 retained by joint pins, which serve as the
fulcrums of said levers; the said levers are
of equal length, and their inner ends are
jointed to each other. Each side of the 105
hanging supports q, q , and equidistant there-
from, the shanks e', e' , and d', d' , of the
screw segments o, o and n, n , are jointed to
the levers p, p ; the said segments move in
guiding mouths which are arranged in such
110

positions that the outer segments n , n —when they are thrown upward by depressing the inner ends of the levers p , p —will match into the coarse threads h' , h' , on the 5 holders m , m , and cause the said holders to move rapidly outward as they are rotated; and when the inner connected ends of the levers p , p , are elevated, the outer segments n , n , will be thrown out of gear with the 10 screw threads h' , h' , and the segments o , o , will be thrown upward into gear with the fine cut screw threads g' , g' , and thereby cause the said holders m , m , to move inward toward each other, as they are rotated. The 15 holes being bored at the same moment into opposite sides of the hub, not only doubles the performance of the machine, but also prevents the bits from exerting any lateral strain upon the chucks. The chucks are re- 20 tained in the desired position while the hub is operated upon by the bits or chisels, by means of the pawl b' , which has a point that fits into holes or recesses in the side of one of the chucks.

25 After the necessary preliminary holes have been bored in the hub, the bits are withdrawn from the holders m , m , (or the holders themselves may be removed,) and then the carriage B, C, is moved endwise, by 30 unscrewing the set screw w , and screwing up the set screw v , until the hub is brought between the upper and lower chisels g , h , which simultaneously form mortises in opposite sides of said hub. The said chisels 35 g , h , are combined with the carrying arms d , b , which project from the rack bars c , a ; the said rack bars are sustained and guided by suitable bearings at the extremities of the bars H, H; and the bars H, H, are sustained 40 by pivots which pass through the metallic plate l' , and the side piece D', of the frame, to which said plate is secured, and the outer ends of said pivots receive the screw nuts k' , k' , shown in Fig. 1. The lower extremity of the said bars H, H, are connected 45 by the toggle jointed levers f , f , with the crank screw e ; the said screw e , works in the guiding hand t , and the screw perforation in the hand t' ; which hands project from a 50 metallic plate that is secured to a standard F, that is connected to the side piece D', of the frame of the machine. It will thus be perceived that by a proper adjustment of the screw e , the bars H, H, can be held in 55 a vertical position, or they may be held in inclined positions for the purpose of giving the proper shape to the ends of the mortises

formed by the chisels g , and h . The teeth in the rack bars a , c , match into the teeth of a cog wheel G, which is placed between them; the journals of the shaft of the said wheel G, works in the plate l' , on the inner side of D', and in the inner bearing brace I, which is secured to the said plate l' , as shown in Fig. 4. The outer end of the shaft 60 of the said cog wheel G, projects beyond the outer side of D', a sufficient distance to receive the operating lever E. It will therefore be perceived that the working of the lever E, will impart a reciprocating motion 65 to the rack bars a , c , which will cause the chisels g , h , to strike the hub A, at the same moment, and thus prevent any straining of the machine, or the changing of the position of the said hub in the chucks, while two 70 mortises are formed during the same time 75 that one is formed by other machines.

What I claim as my invention and desire to secure by Letters Patent, is—

1. The arrangement of the levers p , p , and the segments o , o , and n , n , with the right and left screws g' , and h' , on the peripheries of the bit holders m , m , in such a manner that a proper position of the said levers and segments, will cause the rotary 80 motion of the said holders to move them longitudinally either inward or outward, and which position may be instantly reversed at the pleasure of the person operating the machine, substantially as herein set 85 forth.

2. I also claim arranging the rack bars a , c , and the upper and lower chisels g , h , in such a manner that the said chisels can be made to simultaneously strike upon opposite sides of the hub placed between them, substantially in the manner and for the purpose herein set forth.

3. I also claim arranging the rack bars a , c , the supporting and guiding bars H, H, 100 and the regulating screw e , with each other in such a manner that the chisels g , h , may be made to act in corresponding vertical or oblique directions in forming mortises, substantially in the manner and for the purpose herein set forth.

The above specification of my new and improved machine for making carriage wheels signed and witnessed this third day of May 1855.

CHAUNCEY H. GUARD.
